DESIGN FOR A COMBINED CRUCIFIX AND CANDLE HOLDER

Christopher B. Mulholland, New York, N. Y.

Application August 6, 1949, Serial No. 4,330

Term of patent 14 years

(Cl. D48—2)

To all whom it may concern:

Be it known that I, Christopher B. Mulholland, a citizen of the United States, residing at New York, in the county of New York and State of New York, have invented a new, original, and ornamental Design for a Combined Crucifix and Candle Holder, of which the following is a specification, reference being had to the accompanying drawing, forming part thereof.

In the drawing:

Fig. 1 is a front perspective view of a combined crucifix and candle holder, showing my new design;

Fig. 2 is a side elevational view; and

Fig. 3 is a rear elevational view of the same.

The dotted lines shown in the drawing are for illustrative purposes only.

I claim:

The ornamental design for a combined crucifix and candle holder, as shown and described,
CHRISTOPHER B. MULHOLLAND.
